UNITED STATES PATENT OFFICE.

WILLIAM N. LEWIS, OF ABINGDON, ILLINOIS.

BRUSH-HOLDER.

No. 896,123.

Specification of Letters Patent. Patented Aug. 18, 1908.

Application filed December 24, 1907. Serial No. 407,974.

To all whom it may concern:

Be it known that I, WILLIAM N. LEWIS, a citizen of the United States, residing at Abingdon, in the county of Knox and State 5 of Illinois, have invented certain new and useful Improvements in Brush-Holders; and I do declare the following to be a full, clear, and exact description of the invention, such as will enable others skilled in the art 10 to which it appertains to make and use the same.

This invention relates to new and useful improvements in brush holders.

One of the objects of the invention is to 15 provide a simple, light and durable spring handle of improved construction, and an improved form of adjustable fastening means for fastening the handle in position to a brush or other analogous object.

20 In the accompanying drawings:—Figure 1 is a view in side elevation, illustrating the application of the invention to a brush; Fig. 2 is a vertical sectional view of Fig. 1; Fig. 3 is a plan view of Fig. 1 with parts broken 25 away; Fig. 4 is a cross section taken on line 4—4 of Fig. 1; and Fig. 5 is a detail perspective view of the clamping member.

Referring to the drawings, 1 indicates the improved spring handle, here shown attached to a brush 2, but which may be attached to other analogous articles. The handle comprises a stick 3, preferably of wood and of any form, and a spring member 4. This spring member is formed from a 30 single piece of wire or other flexible element bent to form a socket member 5, the coils at the outer portion of the socket member being of uniform diameter to form a straight body portion 6, and the coils at the inner portion 35 thereof being of less diameter to form an inner reduced portion 7. Before bending the wire to form the socket member it is bent to form a straight loop 8, the latter being preferably disposed at an obtuse angle with the 40 former, the purpose of which will be shown.

45 The fastening means for the loop comprises an upright fastening screw, clamping member and thumb nut, 9, 10 and 11 respectively. The fastening screw is arranged to extend through a corresponding 50 aperture in the back strip 12 of the brush, the head of said screw being arranged against

the inner face of the brush. The clamping member is made from a flat rectangular piece of metal bent to form a curved body portion, 55 and straight side walls 13 and 14, respectively, the edges of the latter being suitably recessed, as at 15, to receive the side pieces of the loop. The thumb nut is adapted to be screwed on the threaded end of the fastening 60 screw and clamp the loop between the clamping member, and the back strip of the brush. By arranging this loop at an inclination, as shown, by slightly lifting the brush at the end of the stroke, the spring member will 65 give the same a quick forward movement and throw the dirt or other debris therefrom. By this arrangement the brush is cleaned automatically and prolongs the life of the bristles as it renders it unnecessary to strike 70 the brush against the floor or other object to cause separation of the dirt therefrom.

In such cases where it is preferable to use the brush endwise fashion, as in cleaning around boxes, in corners or around fixtures, 75 the stick or handle 3 may be swung at right angles to its position as shown in Fig. 1, or arranged in a common plane with the back strip of the brush, by partly unscrewing the thumb nut 10.

80 Having described my invention, I claim:—

In combination with a brush, a spring member comprising a socket member and a flat loop extending from the socket member, a stick attached to the spring member, a 85 clamping member comprising spaced side walls extending across the loop, the outer side edges of the walls of said clamping member being formed with longitudinally spaced recesses to receive the side pieces of the loop, 90 a fastening screw extending through the back piece of the brush, between the side pieces of the loop and the body portion of the clamping member, and a clamping nut screwing on the fastening screw to clamp the loop between the clamping member and back strip 95 of the brush.

In testimony whereof I have hereunto set my hand in presence of two subscribing witnesses.

WILLIAM N. LEWIS.
